GAME BOARD AND PLAYING PIECES FOR A
CHANCE CONTROLLED GAME

Jefferson P. Waldrop, Arlington, Va.

Application March 13, 1945, Serial No. 582,567

6 Claims. (Cl. 273—134)

1

This invention relates to a game apparatus for use in playing a game simulating many of the experiences of everyday life.

While the game apparatus illustrated may, with some variations, be employed for games having various basic themes, it will be described herein as employed in connection with a game the main idea or theme of which is the furnishing of an imaginary post war home with articles now impossible to purchase, paying for the articles partially with "play" war bonds and stamps and partially with such other "monies" as may be accumulated during play of the game as the result of the skill and luck of the players. It is a general object of the invention to provide a game apparatus for use in playing such a game.

For playing the game each player is provided with a card picturing various rooms in a post war house but in each room illustrated one article is represented by a blank depression or recess in the form of that article. These articles may include a new washing machine, a television set, a new refrigerator, automobile or even a helicopter, in other words, articles which will be highly desired by the post war home owner.

The game apparatus includes a main playing board provided with various playing spaces arranged in a definite path of play to which spaces playing pieces or men are moved by the players in turn in accordance with successive throws of dice. Each of the playing spaces bears indicia representing certain financial rights or obligations similar to those encountered in real life. If the playing man of a player is moved to a playing space in accordance with the throw of the dice, the player, depending on the indicia on that space, will be required to pay a bill, pay taxes, pay his insurance or make some other type of payment, or, on the other hand, he may receive money from a stock dividend, from income due him as the result of a gift, or from numerous other sources all as indicated on the particular space.

Certain of the other playing spaces on the main playing board represent the household articles similar to those represented by the blank recesses on the players' cards. If the playing man of a player in accordance with a throw of the dice is moved to one of such spaces, the player may purchase the article represented for his post war home. The main playing board has cut-out pieces shaped like the household articles and when such a purchase is made the player takes such a piece from the playing board and places it in the corresponding recess in his card.

2

A few of the playing spaces on the playing board present to the players opportunities for investment and if a playing man during play lands on such a space the player may invest any amount of his money. Whether the investment succeeds or fails is determined by a spinner disc forming part of the game apparatus.

During the course of play, as will be described, opportunities for trading, selling and borrowing of money on security are also provided.

The winning player is he who is first able to furnish his post war house with all of the desired post war articles and with no financial obligations left to meet.

It will be noted from this general description that the game apparatus makes possible a game involving elements of chance and skill and of the type encountered in everyday life. It is an important object of the invention to provide such a game apparatus.

A preferred form of the game apparatus is illustrated in the accompanying drawings, in which:

Fig. 1 is a plan view of the playing board;
Fig. 2 is a section taken on the line 2—2 of Fig. 1;

Fig. 3 is an enlarged plan view of the central portion of the playing board which central portion is disposed beneath the spinner disc in Fig. 1;

Fig. 4 is a plan view of one of the players' house cards;

Fig. 5 is a section taken on the line 5—5 of Fig. 4;

Fig. 6 is a plan view of the various cut-out pieces employed;

Fig. 7 is a view of the "play" war bonds and stamps employed as "play" currency;

Fig. 8 is a plan view of loan cards employed;

Fig. 9 is a view showing a number of different playing men or pieces, and

Fig. 10 is a perspective view of a pair of dice forming a part of the game apparatus.

In the example illustrated in the drawings, the game is played with a playing board provided with a center spinner; a series of house cards provided with specially shaped recesses or depressions to receive complementary shaped pieces or cut-outs; playing men; a pair of dice; play war bonds and stamps which serve as currency, and a series of cards, called "I-O-Bank Cards," indicating money borrowed from the banker. Before describing the manner in which the game is played, this playing equipment will be described.

With reference to Figs. 1, 2 and 3, it will be noted that the playing board and spinner is con-

structed with a main base board 10 which may be square, circular, or other shape and on which is marked, printed or otherwise disposed a large circle the outer circumference of which is indicated by the reference numeral 11 and the center by the numeral 12. A circumferential edge portion of this circle is divided by a series of radial lines to provide thirty-two playing spaces. These spaces, in a counterclockwise direction around the circle, represent the path of play.

Twelve of these playing spaces, evenly spaced within the circle indicate or represent objects desired by the players. They are as follows: a space 13 marked "Hobby \$200" and having a portion 14 colored blue; a space 15 marked "Helicopter \$800" and having a portion 16 colored gray; a space 17 marked "Library \$400" and having a portion 18 colored purple; a space 19 marked "Bedroom \$300" and having a portion 20 colored brown; a space 21 marked "Recreation \$200" and having a portion 22 colored green; a space 23 marked "Television \$500" and having a portion 24 colored silver; a space 25 marked "Dining Room \$400" and having a portion 26 colored brown; a space 27 marked "Automobile \$800" and having a portion 28 colored red; a space 29 marked "Washer \$200" and having a portion 30 colored yellow; a space 31 marked "Guest Room \$300" and having a portion 32 colored pink; a space 33 marked "Refrigerator \$400" and having a portion 34 colored green; and a space 35 marked "Living Room \$500" and having a portion 36 colored gold.

In addition to the playing spaces described there are four enlarged playing spaces 37, 38, 39 and 40. The space 37 is marked with the word "Begin;" and the other three spaces 38, 39 and 40 are each marked with the word "Spin-Invest or Buy."

Moreover, in the path of play, the following spaces are provided:

Space 41 marked "Have Some Fun—Pay \$50"; Space 42 marked "Income Due—Collect \$500"; Space 43 marked "Taxes Due—Pay \$400"; Space 44 marked "Lucky Number—Collect \$25"; Space 45 marked "Charge Account—Pay \$300"; Space 46 marked "Stock Dividend—Collect \$200"; Space 47 marked "Red Cross Needs Help—Give \$75"; Space 48 marked "Dividend Due—Collect \$100"; Space 49 marked "Bills Due—Pay \$200"; Space 50 marked "Gift—Collect \$75"; Space 51 marked "Insurance Premium—Pay \$100"; Space 52 marked "Bonus—Collect \$300"; Space 53 marked "Improve House—Pay \$500"; Space 54 marked "Debt Paid—Collect \$50"; Space 55 marked "Utility Bill—Pay \$25"; Space 56 marked "Win a Contest—Collect \$400".

Radially inward of the spaces representing the path of play is a superimposed annular ring 57 (see Fig. 2). This ring 57 is marked by radial lines into twelve equal sections 58, 59, 60, 61, 62, 63, 64, 65, 66, 67, 68 and 69. These sections are in radial line respectively with the playing spaces 13, 15, 17, 19, 21, 23, 25, 27, 29, 31, 33, 35 and each is provided with a recess or cut-out portion.

The section 58 radially adjacent playing space 13 is provided with a recess 58' in the shape of a woodworking tool. The section 59 adjacent playing space 15, has a recess 59' in the shape of a helicopter. The section 60 adjacent playing space 17, has a recess 60' in the shape of a book-case. The section 61 adjacent the playing space

19, has a recess 61' in the shape of a chest of drawers. The section 62 adjacent playing space 21 has a recess 62' in the shape of a game table. The section 63 adjacent playing space 23 has a recess 63' in the shape of a television set. The section 64 adjacent playing space 25 has a recess 64' in the shape of a sideboard or commode. The section 65 adjacent playing space 27 has a recess 65' in the shape of an automobile. The section 66 adjacent playing space 29 has a recess 66' in the shape of a washing machine. The section 67 adjacent playing space 31 has a recess 67' in the shape of a dressing table. The section 68 adjacent playing space 33 has a recess 68' in the shape of a refrigerator, and the section 69 adjacent playing space 35 has a recess 69' in the shape of a sofa or davenport.

The central portion of the main playing board 10, inwardly of the annular ring 57, is marked into twelve even segments. This central portion is shown in enlarged plan in Fig. 3. The segment 70 is marked "Collect Investment—No Gain"; the segment 71 is marked "Lose Investment—Plus Three Times Amount"; the segment 72 is marked "Collect Investment—Plus Four Times Amount"; the segment 73 is marked "Lose Investment"; the segment 74 is marked "Collect Investment—Plus Equal Amount"; the segment 75 is marked "Lose Investment—Plus Two Times Amount"; the segment 76 is marked "Collect Investment—Plus Three Times Amount"; the segment 77 is marked "Lose Investment—Plus Five Times Amount"; the segment 78 is marked "Collect Investment—Plus Two Times Amount"; the segment 79 is marked "Lose Investment—Plus Equal Amount"; the segment 80 is marked "Collect Investment—Plus Five Times Amount"; and the segment 81 is marked "Lose Investment—Plus Four Times Amount."

The exact center of the main playing board 10 is provided (see Fig. 2) with an upstanding spindle 84, which supports for rotation thereabout a spinner disc 82, the center of which has a spinning knob 83. The spinning knob 83 has a central bore for rotatably receiving the spindle 84.

The spinner disc 82 has a diameter slightly less than the inner diameter of the annular ring 57. On its upper surface, the spinner disc 82 is marked with a pointer 85, (Fig. 1). The disc 82 is also provided with a segment-shaped cut-out 86 (Figs. 1 and 2) which is disposed so that when the spinner disc 82 is rotated the cut-out 86 will travel over the twelve segments (Fig. 3) on the central portion of the main playing board 10, and when the disc 82 comes to rest, one of these segments may be viewed through the cut-out 86. In Fig. 1, the segment 72 on the main playing board, is shown through the cut-out 86 of the spinner disc 82.

Reference is now made to Figs. 4, 5 and 6 showing one of the house cards each of which is provided with recesses and the cut-outs which are adapted to be placed in these recesses.

In Fig. 4, it will be noted that the house card 87 bears the representations of various rooms of a house having furniture and equipment therein. For each of the room representations of the house there is one item, represented by a depression or recess having the shape of the item. For example, the living room 88 has a recess 89 (see also Fig. 5) in the shape of a sofa. This recess 89 is adapted, during play, to receive a piece cut out in the shape of a sofa 89' shown in Fig. 6. The money value of the sofa 89' is shown on

the house card 87 directly below the representation of the Living Room as being \$500.

Likewise, the dining room 90 has a recess 91 shaped to receive the cut-out commode 91' (Fig. 6); the kitchen 82 has a recess 93 shaped to receive the cut-out refrigerator 93'; the laundry 94 has a recess 95 shaped to receive the washer 95'; the hobby room 96 has a recess 97 shaped to receive the cut-out woodworking saw 97'; the garage 98 has a recess 99 for an automobile 99' and also a recess 100 for a helicopter 100'.

Similarly, the bedroom 101 has a recess 102 for the chest of drawers 102'; the guest room 103 a recess 104 for dressing table 104'; the library 105 a recess 106 for the bookcase 106'; the music room 107 a recess 108 for the television set 108', and the recreation room 109 a recess 110 for the game table 110'.

In each instance, the dollar purchase price of the cut-out is indicated on the house card 87 directly below the room in which the item is to be located.

The lower portion of the house card 87 also has indicia indicating the "Loan Value on Items Owned."

It will be understood that there should be one house card 87 for each player and also one of each of the cut-outs for each player in the game.

The remaining equipment necessary to play the game is illustrated in Figs. 7, 8, 9 and 10.

In Fig. 7 there is illustrated some "play" war bonds and stamps. These are used in place of money. Of the \$500 denomination bonds 111, six will be distributed to each player; of the \$100 denomination bonds 112, ten will be distributed to each player; of the \$50 denomination bonds 113, twelve will be distributed to each player; of the \$25 denomination bonds 114, twelve will be distributed to each player, and of the \$10 denomination war stamps 115, ten will be distributed to each player. The total amount distributed to each player is \$5,000, which is the cost of all articles needed for furnishing one house.

In Fig. 8, cards representing loans made by the bank to a player are indicated. The card 116 has an indication of a "Loan Value \$150" and also an indication "I-O-Bank \$160"; the card 117 bears a "Loan Value \$225" and the amount owed to the bank, \$240; the card 118 recites a "Loan Value \$300" and indicates that the player owes the bank, \$320; the card 119 says "Loan Value \$375" and indicates that the player owes the bank, \$400; and the card 120 has an indication, "Loan Value \$600" and indicates that the player owes the bank, \$640. The manner in which these cards are employed in the game will be described hereinafter.

In Fig. 9, there is illustrated a number of different playing men. Each of these men is different from the other and each of the players in the game is provided with one playing man. These may be formed with a round or square base with a superposed portion which is preferably in the shape of some household article or the like. For example, the playing man 121 has an upper portion in the shape of a radio tube; the playing man 122 in the shape of an automobile tire; the playing man 123 in the shape of a stepladder; the playing man 124 in the shape of an electric toaster; the playing man 125 in the shape of a cup or bowl; the playing man 126 in the shape of an electric light bulb; and the playing man 127 in the shape of a glass or the like.

Finally, Figure 10 represents a pair of dice 129,

Having now described the various playing equipment, one manner in which the game may be played therewith is as follows:

The playing board is first loaded with twelve different cut-outs 89', 91', 93', 95', 97', 99', 100', 102', 104', 106', 108' and 110', one of such cut-outs of each kind for each player participating in the game. These cut-outs are placed on the playing board 10 in the corresponding recesses 69', 64', 68', 66', 58', 65', 59', 61', 67', 60', 63' and 62'.

House cards 87 are then given out, one to each player participating in the game. As indicated, all these house cards are identical. Next, each player chooses a playing man 121-127. One player, who may be any one of the group, is chosen as a banker and he in turn distributes the war bonds and stamps to each player in the amounts recited above. The banker during play also takes in and gives out bonds and stamps and the loan cards 116 to 120, inclusive, to players as needed and as will be later explained.

The player rolling high dice begins the game. One throw is allowed to each player.

The object of the game is to furnish a house completely and be clear of all debt. This object is attained when all recesses, such as 89, 91, 93, etc., on a player's house card 87 have been filled with their respective cut-outs 89', 91', 93', etc., and all loans have been repaid to the banker.

The play begins as the starting player places his playing man, say 121 on the space 37 marked "Begin," throws the dice, and moves his playing man 121 the number of spaces indicated on the dice. The play is counterclockwise as indicated by the arrow.

If, for instance, the playing man 121 is moved, in accordance with the throw of the dice, to the space 42, the player will collect \$500 in bonds from the banker. If, for example, the dice show "5," the player will move his man to the space 43 and will pay the banker \$400 which are the taxes indicated on that space.

If the player lands on a space indicating an article to be purchased and represented by one of the recesses 58' to 69', inclusive, he may buy the article by paying the banker the amount shown to be the purchase price. He then removes the article from the recess on the playing board 10 and places it in its corresponding recess on his house card 87. If, for example, his playing man moves to the space 15 marked "Helicopter \$800," the player pays the banker \$800, removes one of the helicopter pieces 100' from the recess 59' in the playing board and places it on his house card 87 in the recess 100.

When a playing man lands on one of the spaces 38, 39 or 40 marked "Spin—Invest or Buy," the player has a choice of either making an investment or making a purchase, or if he desires to do neither he may take no action at all and wait until his next turn at the dice. If he elects to make an investment he announces his choice and the amount that he wishes to invest, and places war bonds in that amount at the edge of the playing board. He then spins the spinner disc 82 and reads the results through the cut-out 86 on the spinner. For instance, if he chooses to invest \$100, he states that he will invest \$100 and places \$100 in war bonds on the edge of the board.

If the spinner cut-out 86 on stopping exposes the space 72 marked "Collect Investment—Plus 4 Times Amount," the player withdraws his \$100 and collects in addition \$400 from the banker. If, conversely, he spins and the spinner cut-out 75 86 exposes the space 81 (Fig. 3) marked "Lose

Investment—Plus 4 Times Amount of Investment," the player pays the \$100 invested and an additional \$400 to the banker.

If a playing man is moved to a space 38, 39 or 40 and the player elects to purchase, he spins the spinner and purchases the object to which the pointer 85 points by moving his playing man to the space indicating the article and paying the banker the amount of the purchase price. He then removes the article or cut-out from the playing board, and as previously explained, places it in its respective place on his house card 87. If, however, the pointer 85 on spinning comes to rest on a space already occupied by another player's playing man, the player spinning cannot move his playing man to that space and purchase, but must move his playing man back to the space 37 marked "Begin."

Each time a player throws "doubles" on the dice, he is entitled to another throw.

Play follows in rotation around the board counterclockwise, each player moving his playing man and taking action as described.

When the throw of the dice indicates that a player is to move his man to a space already occupied by another player's playing man, he cannot move to that space regardless of the benefit or penalty indicated on that space but must return his playing man to the space 37 marked "Begin." The only exception to this playing rule being that if the dice indicate he is to move to one of the spaces 38, 39 or 40 marked "Spin—Invest or Buy," he may move his playing man to that space regardless of whether another player's playing man is already there.

If during the progress of the game, a player lands on a space designating an article or cut-out which the player already possesses, he may, if he chooses, purchase another similar article and hold the same with the view of selling at a profit at any time during the game to another player who may need it. For example, the player throwing the dice may already have a game table 110 for the recess 100 in the recreation room 109 on his house card 87. If the throw of the dice indicates he is to move his playing man to the playing space 21, he may pay the banker \$200 and buy another game table and hold it for possible future sale to another player.

Any player holding surplus articles may retain these objects until he is able to obtain the price he desires for them, except in the following instance: when all of the articles or pieces indicating a particular object have been bought by the several players and one of the players who needs this particular article or piece lands on a playing space indicating such object, the player requiring the article may demand that the player holding such article as surplus release it for sale. In this case, the player holding the article endeavors to obtain a good price from the player demanding its release. If an agreement on the price of sale cannot be reached between the two players, the player holding the article as surplus must return it to the playing board 10 and the banker will pay him one-half of its original cost. The player requiring the article, however, will then be forced to wait until he again lands on the playing space indicating this article, before he may purchase it.

No player can demand release of any surplus article held by another player merely because he lands on a playing space giving him the right to his purchase. He must need the article to complete or fill a particular recess in his house

card 87. Nonplayer can demand release of surplus articles held by another player as long as there is a similar article on the playing board that can be purchased.

As the game progresses, some players may find that their funds become diminished and that they will require loans from the banker. Each article has a loan value, which is indicated, as described, on the lower portion of each house card 87. A player may borrow the full loan value on any article which he already possesses on his house card. He may receive from the banker the amount of the loan value and the banker will give him the appropriate loan card 116 to 120 inclusive. These loan cards, as heretofore stated, indicate the amount borrowed from the banker and also the amount to be paid back to the banker when the loan is repaid. When making a loan the player places the loan card which he receives from the banker on his house card 87 over the article by which the loan is secured, where it remains until the loan is repaid, at which time the loan card is returned to the banker. It will be noted that the amount indicated on each loan card as being owed to the bank is in each case greater than the value of the article, that is, the amount received from the bank. The difference of course represents interest on the loan.

It is best that no loan should be made by any player who possesses any surplus articles, until such surplus articles or articles are either traded to another player for some article which the player requires for completing his own house card, or are sold to some other player, or are sold to the banker for half price and replaced on the playing board.

If all of the articles on a player's house card 87 are covered by loan cards, and he has no more money, he may stay in the game hoping to recoup his losses by landing on one of the favorable playing spaces, giving him additional money, but if he then lands on a playing space demanding a payment of some kind, he must drop out of the game.

A player may have his house card completely filled with the desired articles and yet have an article on his house card covered by a loan card. In this case he must continue playing until he has collected enough money to pay off the loan and return his loan card to the banker.

The winning player is the player who has successfully filled all of the recesses in his house card 87 with the articles 89', 91', 93', 95', 97', 99', 100', 102', 104', 106', 108', and 110', and has no loan cards 116 to 120, inclusive, covering objects on his house card.

If so desired, the winning player may drop out, and the game may continue to determine winner a second place. In this case, the winner's completed house card and his playing man are removed from the playing board and any surplus money held by him is returned to the banker.

When two players are able to finish simultaneously as the result of a trade, the player having the greater amount of money wins.

When a player is forced to drop out of a game for any reason, his house card, together with articles previously purchased by him, his playing men, and any money remaining in his possession are all withdrawn from play.

It should be obvious that modification in the manner of playing the game may be made within limits, the game described being the preferred

type of game for the game apparatus illustrated and described.

With relation to the game apparatus, it is also apparent that some changes in the form and arrangement of the parts, the arrangement of the playing spaces and the particular indicia thereon may be made without departing from the invention. For example, the spinner disc in the center of the main playing board may be replaced by a simple pointer which spins about the spindle. Moreover, the annular ring 51, instead of being disposed inwardly of the playing spaces 31, 13, 41, 42, etc., may be disposed outwardly of these playing spaces. Now that the invention has been disclosed, these and other changes will occur to those skilled in this art.

It should be borne in mind that the description given is only by way of example and that the invention is only to be limited as indicated in the claims which follow.

I claim:

1. In game apparatus of the type with which playing men are advanced along playing spaces of a plurality of types on a game board in accordance with chance means and with which a spinner is provided to designate certain chance spaces, the novel features comprising the provision of indicia in a first type of said playing spaces designating the purchase value of various different household articles which may be purchased by a player whose playing man is moved to playing spaces of said first type, a plurality of playing pieces having the shapes of said different household articles, said game board adjacent the playing spaces of said first type having recess means complementary in shape to said playing pieces and in which said playing pieces may be disposed, a second type of said playing spaces bearing indicia designating opportunities for investment, and indicia in said chance spaces designating the outcome of said investments, whereby players whose playing men alight on one of said first type of playing spaces may purchase and remove the household article disposed in the adjacent recess while players whose playing men alight on one of said second type of playing spaces may invest and determine the outcome of the investment by spinning said spinner.

2. Game apparatus as set forth in claim 1 and in which said playing spaces are circularly disposed, said recesses being disposed radially of and adjacent playing spaces of the first type, said chance spaces being disposed in a circular manner concentrically inwards of said circularly disposed playing spaces.

3. Game apparatus as set forth in claim 1 and a plurality of smaller boards, one for each player, each of said smaller boards bearing representations of rooms of a house and having recess means in each room having the shapes of said different household articles for receiving the appropriate playing pieces as they are purchased by the player during the course of play.

4. Game apparatus as set forth in claim 1, in which said playing spaces are disposed in a circular path, a third type of said playing spaces bearing indicia designating monies to be paid to or by a player for reasons simulating those occurring in real life, said recesses being formed in a raised annular ring disposed on said game board concentrically inwards of said playing spaces, said chance spaces being disposed in a circle disposed concentrically inwards of said ring.

5. In game apparatus of the type with which playing men are advanced along playing spaces of a plurality of types on a game board in accordance with chance means and with which a spinner is provided to designate certain chance spaces, the novel features comprising the provision of indicia in a first type of said playing spaces designating the purchase value of various different household articles which may be purchased by a player whose playing man is moved to playing spaces of said first type, a plurality of playing pieces having the shapes of said household articles, said game board adjacent the playing spaces of said first type having structure complementary in configuration to said playing pieces for engaging said playing pieces, a second type of said playing spaces bearing indicia designating opportunities for investment, and indicia in said chance spaces designating the outcome of said investments, whereby players whose playing men alight on one of said first type of playing spaces may purchase and remove the household article disposed on the adjacent structure while players whose playing men alight on one of said second type of playing spaces may invest and determine the outcome of the investment by spinning said spinner.

6. In game apparatus of the type with which playing men are advanced along playing spaces of a plurality of types on a game board in accordance with chance means and with which a spinner is provided to designate certain chance spaces, the novel features comprising the provision of indicia in a first type of said playing spaces designating the purchase value of various different household articles which may be purchased by a player whose playing man is moved to playing spaces of said first type, a plurality of playing pieces bearing representations of said different household articles, said game board adjacent the playing spaces of said first type having recess means for receiving said playing pieces and in which said playing pieces may be disposed, a second type of said playing spaces bearing indicia designating opportunities for investment, and indicia in said chance spaces designating the outcome of said investments, whereby players whose playing men alight on one of said first type of playing spaces may purchase and remove the household article disposed in the adjacent recess while players whose playing men alight on one of said second type of playing spaces may invest and determine the outcome of the investment by spinning said spinner.

JEFFERSON P. WALDROP.
